VARIABLE CAPACITY RECORD BINDER

Paul O. Unger, Glen Ellyn, Ill., assignor to Wilson-Jones Company, Chicago, Ill., a corporation of Massachusetts

Application October 29, 1932, Serial No. 640,136

13 Claims. (Cl. 129—1)

This invention relates to a loose leaf binder of the record book type that may be expanded to vary the capacity of the binder.

Heretofore record binders have been made with certain fixed capacities. Such fixed capacity binders often prove to be unsatisfactory because a slight increase in the thickness of sheets will make it impossible to insert the required number of sheets in the binder. If the sheets are slightly thinner than those for which the binder is designed, the specified number of sheets will not completely fill the binder.

Another obvious disadvantage of a fixed capacity record binder is the possibility that the records for any particular year may vary considerably from the estimates in accordance with which the record binders were ordered. In practically all governmental agencies recording vital statistics, it is required to keep the records for each year separate. Accordingly, if certain records surpass the estimates for that year, it is necessary to buy additional record binders.

It is an object of this invention to provide a record binder of variable capacity. It is a further object of this invention to provide a variable capacity record binder in which each end may be compressed independently of the other and in which the back is always centered regardless of the relative positions of the ends. It is a further object of this invention to provide a record binder in which the entire contents may be readily removed from the binder and handled without difficulty. It is a further object of this invention to provide a variable capacity record binder having means to lock the binder permanently when it is filled so that nobody can tamper with the contents of the binder without leaving evidence of such tampering. Other objects of this invention will become apparent upon reading the following description taken in conjunction with the accompanying drawings in which:

Figure 1 is a perspective view of a binder embodying my invention;

Figure 2 is a plan view of the back with portions broken away to facilitate the illustration;

Figure 3 is an end elevation of the binder with portions broken away to facilitate the illustration;

Figure 4 is a fragmentary plan view of the back with portions broken away to show the permanent locking means in position;

Figure 5 is a cross section taken along the line V—V of Figure 4;

Figure 6 is a side elevation of Figure 5;

Figure 7 is a perspective view of the post-carrying bar;

Figure 8 is a perspective view of the lock bar; and

Figure 9 is a perspective view of one type of locking pin.

In the drawings the reference numerals 2 and 3 refer to a pair of back sections movable transversely relative to each other. The ends of the section 2 are bent over to form the channels 4 and 5 adapted to guide the section 3 in its transverse movement. The channel member 4 is provided with an aperture 6, and the channel member 5 is provided with a similar aperture 7, for a purpose hereinafter described. The back section 3 is provided adjacent each end with a series of projections 8.

A lock bar 9 has its ends positioned within the channel members 4 and 5 and is provided with ears 10 and 11 adapted to project through the apertures 6 and 7, respectively. The ear 10 has a portion bent over parallel to the body of the lock bar, as indicated at 12. The lock bar 9 is provided adjacent each end with a series of projections 13 adapted to cooperate with the projections 8 to retain the back sections in any desired position.

A lever 14 pivoted to the channel member 4 by means of a rivet 15 is provided with a slot 16 through which the ear 10 projects. The turned over portion 12 prevents the separation of the ear and lever. The lever has its free end bent to form a finger piece 17. The lock bar 9 may be moved longitudinally into and out of locking position by manipulation of the lever 14. The lock bar is notched, as indicated at 18, to allow sufficient clearance for the lock bar to be moved out of locking position, without binding against the rivet 15.

The binder is provided with an outer back plate 19 which includes an outer round metal plate 20 and an inner plate 21 welded or riveted together. The end of the plate 20 is bent up, as indicated at 22, to give the end of the binder a finished appearance. The outer plate 20 may be suitably decorated or covered with binding material of any desired kind. The plate 21 is provided with a central depressed portion 23 extending longitudinally of the binder. A pair of short aligned slots 24 and 25 are positioned adjacent opposite ends of the depressed portion of the plate.

Toggle links 26, 27, 28 and 29, respectively, are pivotally secured to opposite ends of the back sections 2 and 3, as indicated at 30, 31, 32 and 33. The inner ends of the toggle links 26 and 28 are

pivotedly connected to a pin 34 slidable in the slot 24. The inner ends of the toggle links 27 and 29 are similarly pivoted on a pin 35 slidable in the slot 25. The independence of the floating 5 toggles at each end of the binder results in the centralization of the back plate 19 with respect to the back sections 2 and 3 at each end of the binder regardless of any possible difference in thickness of contents at opposite ends of the 10 binder. Accordingly, each end of the binder may be compressed independently of the other, and the outer back plate will always remain properly centered.

The outer edges of the back sections 2 and 3 15 are bent up at right-angles to form flanges 36 and 37, respectively. Filler strips 38 and 39, respectively, are placed in juxtaposition to the flanges 36 and 37 and inverted U-shaped members 40 and 41 each embrace one flange and its 20 juxtaposed filler strip. Each group of three members is welded to form a unitary structure.

The outer edges of the U-shaped members 40 and 41 have curved ears, as indicated at 42 and 43 respectively, to form parts of hinges for hinging the cover members 44 and 45 to the binder. 25 A metal plate 46 (Figure 5) embedded in each cover has its free edge provided with curved ears, as indicated at 47, to complete the hinge barrels. The hinge pintles 48 have their ends covered with 30 caps 49. The caps 49 are of comparatively soft material and are larger in outside diameter than the hinge barrel to protect the finish of the desk or other article of furniture on which the binder may be handled.

35 Each of the two units, comprising the members 36, 38 and 40 in one instance and 37, 39 and 41 in the other, is provided with a plurality of apertures 50 adapted to receive short posts 51 extending from one wall of a post-carrying bar 52. 40 The bar 52 is U-shaped in cross section and has a plurality of apertures 53 through its closed edge. A plurality of sheet-retaining posts 54 have one end bent at right angles and extending into the apertures 53 and between the walls of 45 the bar 52. The short posts 51 extend through both walls of the bar 52 and the ends of posts 54 to secure the posts 51, the bar 52 and the sheet-retaining posts 54 together in one rigid unit. The posts 54 on the bar 52 are staggered 50 with respect to the posts 54 on the bar adapted to be positioned on the other side of the binder to avoid mutual interference of the two sets of posts. The sheet retaining posts 54, as shown in Figure 7, are of double thickness. Doubling 55 the material also has the advantage of insuring perfectly smooth edges for the post without necessitating expensive finishing operations.

As shown in Figures 4, 5, 6 and 9, the record 60 binder may be locked permanently against expansion when it is filled and it is no longer necessary to insert or remove sheets. The members 36, 38 and 40 are provided with an aperture 55 adjacent the top edge of the binder. The aperture 55 is adapted to receive a locking pin 56 which has a split end 57. The two parts of the end 57 are sufficiently resilient to enter the aperture 55 and the pin cannot be removed therefrom because the end 57 is too wide. The aperture 55 is positioned so that the locking pin enters between the ear 11 of the lock bar 9 and the downturned wall 58 of the channel member 5. The end wall 59 of the channel member 5 is also turned down to prevent the locking pin 56 from being driven past the ear 11. In addition to preventing longitudinal movement of the lock bar 70 75

9 that would allow the projections 13 to move out of engagement with the projections 8, the locking pin exerts vertical pressure on the lock bar 9 to prevent vertical separation of the inter-engaged projections.

The operation of my binder may be summarized as follows:

A plurality of suitably punched sheets 60 are mounted on the sheet-retaining posts of a pair of bars 52. The posts 51 are then positioned in the apertures 50, the lock bar 9 is moved from the position shown in Figure 1 to locking position shown in Figure 2 and the back sections 2 and 3 are compressed. When it is desired to insert or remove a sheet, the finger piece 17 is manipulated to move the lock bar 9 to disengage the projections 8 and 13. The top cover is then moved to free the post carrying bar 52. If desired, the sheets may be retained between the two bars 52 and transferred from one binder 20 to another.

It will be seen that I have devised a strong and durable record binder in which the sheets may be held under temporary compression when the binder contains current records and under permanent compression after it is no longer necessary to insert or remove sheets from the binder. The locking pin which constitutes the permanent lock does not interfere with subsequent additional compression so that if the records are 30 wrinkled, as in the case of photostatic records, the binder may be permanently locked with the sheets under whatever compression is attainable at that time. As the sheets become flattened, the compression may be maintained by forcing 35 the back sections together to as great an extent as possible.

It is advantageous to keep the sheets in a record binder under compression because then when the sheets in the binder are handled, the wear 40 is not on the portions of the sheets adjacent the holes, as in previous record binders, but is on the imperforate area of the paper adjacent the hinge. This increases the life of the individual sheets considerably.

Another advantage of keeping the sheets always under compression is that it makes it impossible for anyone to surreptitiously remove an entire sheet from the binder. The stub of any sheet torn or cut out of the binder always remains as visible evidence of the tampering.

While I have described a preferred embodiment of my invention in detail, it will be understood that the description thereof is illustrative rather than restrictive, as many details may be modified or changed without departing from the spirit or scope of my invention. Accordingly, I do not desire to be restricted to the exact construction described except as limited by the appended claims.

I claim:

1. In a loose leaf binder, removable sheet retaining means comprising a bar U-shaped in cross section provided with an aperture through its closed edge, a sheet retaining post having an end portion extending within said bar through said aperture, and means for securing said end portion to said bar, said securing means projecting beyond said bar to cooperate with said binder to removably secure said sheet retaining means in said binder.

2. In a loose leaf binder, removable sheet retaining means comprising a bar, a sheet retaining post, and means for securing said post to said bar, said securing means passing through said

bar and post and projecting therebeyond to cooperate with said binder to removably secure said sheet-retaining means in said binder.

3. In a loose leaf binder, a pair of back sections, the ends of one of said back sections being provided with channels in which said other back section may slide, a lock bar having its ends disposed in said channels, and means pivoted on one of said channel members for moving said lock bar into and out of locking position.

4. In a loose leaf binder, a pair of back sections, the ends of one of said back sections being bent to form channels in which said other back section may slide, each of said channel members being provided with an aperture in its upper surface, a lock bar having its ends disposed in said channels and having ears extending through said apertures to retain said bar in position in said binder, and means engaging one of said ears for moving said bar into and out of locking position.

5. In a record binder, a pair of back sections, a pair of channel members on the ends of one of said back sections in which said other back section is adapted to move transversely relatively to said first mentioned back section, a lock bar, cooperating means on said lock bar and said second mentioned back section to temporarily prevent relative outward movement of said back sections, and means to permanently prevent such movement.

6. In a record binder, a pair of back sections capable of relative transverse movement, a lock bar slidable longitudinally of said back sections, cooperating means on said lock bar and one of said back sections to temporarily prevent relative outward movement of said back sections, and means to permanently prevent such movement.

7. In a record binder, a pair of back sections capable of relative transverse movement, a plurality of projections on one of said back sections, a lock bar, a projection on said lock bar, means to slide said lock bar longitudinally relative to said one back section to move said projections into and out of locking engagement, and means to permanently prevent said longitudinal movement.

8. In a record binder, a pair of back sections, the ends of one of said back sections being provided with channels in which said other back section may slide, each of said channel members being provided with an aperture in its upper surface, a lock bar having its ends disposed in said channels and having ears extending through said

apertures to retain said bar in position in said binder, means engaging one of said ears for moving said bar into and out of locking position, and means insertable between one of said ears and the end wall of its associated channel member to permanently prevent movement of said lock bar out of locking position.

9. In a record binder, a pair of back sections movable transversely relative to each other, a pair of apertured flanges extending along opposite longitudinal edges of said back sections, a pair of post-carrying bars, each of said bars being provided with short posts to fit in the apertures in said flanges and with sheet-retaining posts adapted to hold a plurality of sheets within said binder, a lock bar adapted to cooperate with said back sections to retain said post-carrying bars in said binder, and means to permanently prevent movement of said lock bar to unlocked position.

10. In a loose leaf binder, a pair of back sections normally capable of relative transverse movement, a lock bar associated with said back sections, said lock bar being movable longitudinally into and out of locking engagement, a flange on one end of said lock bar, a flange on one of said back sections adapted to cooperate with said first mentioned flange to limit the longitudinal movement of said lock bar, and non-removable means insertable between said flanges to prevent longitudinal movement of said lock bar.

11. In a loose leaf binder, a pair of back sections normally capable of relative transverse movement, a lock bar associated with said back sections, and a non-removable pin insertable between portions of said lock bar and one of said back sections to permanently prevent transverse separation of said back sections.

12. In a loose leaf binder, removable sheet retaining means including a double walled bar, a sheet retaining post having an end portion positioned between the walls of said bar, and means passing through said walls and said post to secure said post to said bar.

13. In a loose leaf binder, removable sheet retaining means including a bar U-shaped in cross section provided with an aperture through its closed edge, a sheet retaining post having an end portion extending within said bar through said aperture, and means passing through said bar and said post to secure said post to said bar.

PAUL O. UNGER.
